Specification for Design.

Patented Apr. 8, 1913.

Application filed July 24, 1912. Serial No. 711,347. Term of patent 3½ years.

To all whom it may concern:

Be it known that I, ADOLPH COPELAND, a citizen of the United States, residing at Chicago, in the county of Cook, State of Illinois, have invented a new, original, and ornamental Design for Show-Stands, of which the following is a specification, reference being had to the accompanying drawing, forming part thereof.

The figure is an elevation showing my new design.

I claim:—

The ornamental design for a show stand, as shown.

ADOLPH COPELAND.

In presence of—

HARRY BROWN,
ARTHUR KUELICH.
